DENTAL CABINET

Jack H. Levey, Los Angeles, Calif.

Application February 6, 1958, Serial No. 49,521

Term of patent 7 years

(Cl. D24—1)

Fig. 1 is a perspective view showing a dental cabinet embodying my new design, with the end doors in closed position.

Fig. 2 is a perspective view of the same, with the end doors and the top of the hamper in open position.

Fig. 3 is an enlarged sectional view taken on line 3—3 of Fig. 2.

The rear and right side of the cabinet are substantially plain.

The dominant features of my design reside in the full line portions of my drawing.

I claim:

The ornamental design for a dental cabinet, substantially as shown and described.
